UNITED STATES PATENT OFFICE.

TALBOT G. MARTIN, OF CHICAGO, ILLINOIS, ASSIGNEE, BY MESNE ASSIGNMENTS, TO
FIRST TRUST AND SAVINGS BANK, TRUSTEE, OF CHICAGO, ILLINOIS.

TELEPHONE-EXCHANGE SYSTEM.

1,123,339.

Specification of Letters Patent. Patented Jan. 5, 1915.

Application filed June 16, 1906. Serial No. 322,080.

To all whom it may concern:

Be it known that I, TALBOT G. MARTIN, a citizen of the United States of America, and resident of Chicago, Cook county, Illinois, have invented a certain new and useful Improvement in Telephone-Exchange Systems, of which the following is a specification.

My invention relates to telephone systems in general, but more particularly to automatic or semi-automatic telephone systems, and especially to extension or party line systems.

Generally stated, the object of my invention is to provide improved means for preventing interference between subscribers on the same extension or party line.

It will be seen that my present invention is in the nature of an improvement on the extension or party line telephone system disclosed in my prior application Serial No. 289,048, filed by me in the United States Patent Office on the 25th day of November, 1905. In said prior application a substation relay is employed for removing the substation ground connection from the control of any extension or party line subscriber who attempts to use his telephone after the line is once temporarily appropriated for use by another subscriber on the same line. Also, in said prior application, the switch-hook is connected for mechanically restoring the armature of the said relay after the latter has been operated.

My present invention, however, contemplates certain improvements by which the switch-hook is relieved of this work, and whereby the said ground controlling relay is restored by an electro-magnet or relay, which latter may be termed a releasing relay.

I also now provide certain improvements in the first-selectors, together with certain novel combinations and circuit arrangements and details of construction tending to increase the general efficiency of a telephone system of this particular character, as will hereinafter more fully appear.

To the foregoing and other useful ends, my invention consists in matters hereinafter set forth and claimed.

Figure 1 shows in diagram the circuits and apparatus involved when one substation of a telephone line is in connection with another substation of another telephone

line, the calling subscriber being shown at the left and the answering subscriber at the right. It will be understood, of course, that in this case it makes no difference whether a line is an extension line or a party line. The elements comprised in the said connection, shown in Fig. 1, are a calling substation #110, the first-selector A, the central battery B, the connector C, the called first-selector A¹, the called substation #220, the party substation D on the calling line, and the party substation E on the called line. The subscriber at substation D is shown locked out, having raised his switch-hook after the subscriber #110 obtained control of the line. Fig. 2 is a similar view showing the circuits and apparatus involved when a subscriber calls another subscriber on the same line. The line here represented is the calling line in Fig. 1, and in addition to the substations #110 and D the substation F #210 is also shown. The substation #110 is also the calling substation, while the called substation is the station F #210, the substation D being again shown locked out for the same reason stated in connection with Fig. 1. Fig. 3 is a diagrammatic perspective view of the selector-switch A. Fig. 4 is a similar view of the connector C. In these figures the central battery is shown in a number of places, but it will be understood that but one battery may be employed having its positive terminal preferably grounded at G. Figs. 5, 6, 7, 8 and 9 are detail views of the substation circuit controlling and restoring relays H and I, respectively, mounted upon a frame O.

The substation telephone equipment may be of any well-known or approved type. The substation illustrated in Fig. 1 comprises the usual switch-hook 2, the receiver 3, transmitter 4, primary winding 5 of the induction-coil 6, the battery 7, secondary winding 8 of the induction-coil 6, condenser 9, and ringer 10. The switch-hook has a number of cam-arms 11, 12, 13 and 14. The cam-arm 11 controls the springs 15 and 16; the cam-arm 12 controls the ground springs 17 and 18; the cam-arm 13 controls the springs 19, 20, 21, 22, 23 and 24; and the cam-arm 14 controls the release-springs 25, 26 and 27. The substation signaling or ringing button 28 controls the spring 29 with respect to the contact-points 30 and 31. The calling device for the subscriber is rep-

resented by the push-buttons 32 and 33, springs 34 and 35, contact-points 36 and 37, and ground post 38. The substation circuit-controlling relay H is provided with an armature 39 for controlling the springs 40, 41, 42, 43 and 44. A latch 45 is provided for locking the armature 39, which latch is controlled by the spring 46. The substation release-relay I is also provided with an armature 47 for controlling the armature 39 of the relay H, and for controlling the latch 45. The said relay I, by means of its armature 47, controls the energizing circuit of the relay H through the medium of the springs 48 and 49. It will be understood, of course, that the other substations herein shown are the same.

The selector A may also, like the substation, be of any desired or approved general character. The type herein described is of the general class disclosed in Patent No. 815,321, granted March 13, 1906, to Keith, Erickson & Erickson. Said selector is provided with a shaft 50 for carrying the line wipers 51 and 52 and the private wiper 53. The said shaft is operated vertically by the vertical magnet 54 and may be raised to any one of ten positions for placing the said wipers on a level with any one of the rows of contacts of the line and private banks 55 and 56, respectively. Being raised, the shaft may be rotated by a rotary magnet 57. The release-magnet 58 is employed for restoring the switch after it has been operated. The vertical and rotary line relays 59 and 60, the bridge-cut-off-relay 61, the back-release-relay 62, and the private magnet 63 are auxiliaries for controlling the vertical, rotary and release magnets 54, 57 and 58. When the calling subscriber operates the vertical line relay 59 by sending impulses from the substation through said relay, the vertical magnet 54 is operated, which latter then raises the shaft 50; and when the subscriber energizes the rotary line relay 60 the private magnet 63 is energized for operating the side switch K. The said side switch is a step-by-step mechanism adapted to move from first to second position and from second to third position. When the private magnet 63 operates for the first time the side switch passes to second position, establishing an energizing circuit for the rotary magnet 57, which latter then automatically operates to rotate the shaft carrying the shaft-wipers 51, 52 and 53 into connection with some suitable trunk-line; and as soon as the trunk-line is found the side switch K passes to third position, destroying, therefore, the energizing circuit of the rotary magnet, and connecting the subscriber's line with a trunk-line. The selector-switch may be released by one of two methods—that is, either directly from the line, or over the seized trunk. In the former case the vertical and rotary line re-

lays 59 and 60 are energized simultaneously and a circuit is then set up through the release-magnet 58. This release, however, can only take place before the side switch passes to third position. In the latter case a circuit is closed at the switch at the other end of the seized trunk-line, which comprises the private wiper 53 and the back-release-relay 62. This relay 62 upon energizing closes a circuit through the release-magnet 58; but this can only happen when the side switch is in third position. When the selector is operated a guarding potential is established from the selector to the connector banks, by way of the so-called private normal, to prevent any subscriber from calling in on the line of the selector while the line is in use. When a subscriber calls another subscriber on his own line the connection is completed by means of a connector, and unless special provision is made for the removing of the guarding potential that is established when the selector is first operated it would therefore be impossible for one subscriber to call another subscriber on the same line. To meet this requirement the selector is provided with a private normal relay 64 which removes the guarding potential at the instant that the connector controlled from a certain line starts to establish connection with the same line.

The connector may be of any suitable or approved type, such, for instance, as a connector of the general type described in Patent No. 815,176, granted March 13, 1906, to Keith, Erickson & Erickson. The construction of the connector is quite similar to that of the selector, although the circuits of the former are quite different from those of the latter. The switch-shaft 65, the wipers 66, 67 and 68, the line and private banks 69 and 70, the vertical and rotary line relays 71 and 72, the vertical magnet 73, the rotary magnet 74, the release-magnet 75, the private magnet 76, and the side switch L are similar to those of the selector. The connector has a ringer-relay 77 for bridging the ringer-generator 78 across the called subscriber's line to signal the called subscriber. When the vertical line relay 71 is energized for the first time the vertical magnet 73 is operated to raise the shaft 65, and when the rotary line relay 72 is energized for the first time the private magnet 76 operates to shift the side switch L to second position. The shifting of the side switch removes the vertical magnet 73 from the control of the vertical line relay 71 and substitutes therefor the rotary magnet 74. The rotary magnet does not operate automatically, as is the case with the rotary magnet of the selector, but operates step-by-step in accordance with each electric impulse directed by the subscriber to operate the vertical line relay 71 the second time. When the rotary line relay 120

72 is operated the second time the private magnet 76 is again actuated and the side switch L passes to third position, removing in turn the rotary magnet 74 from the control of the vertical line relay 71 and substituting for the said rotary magnet the ringer-relay 77. Said ringer-relay becomes energized when the vertical line relay 71 is subsequently energized by the calling subscriber 10 pressing the signaling button 28.

In a general way the operation of the system is as follows: When the subscriber removes his receiver 3 he permits the switch-hook 2 to rise, removes the ringer 10 from across the line, substitutes instead the secondary circuit comprising the receiver 3 and the secondary winding 8 of the induction-coil 6, closes a local energizing circuit through the transmitter 4 and primary winding 5, and establishes a ground connection to the ground post 38 of the calling device, and to the release-spring 25 and the contact-point 31 of the signaling device. The calling subscriber then proceeds by 20

pressing the buttons 32 and 33 of the calling device, thereby operating the first-selector A, causing the side switch to place the switch-shaft wipers 51, 52 and 53 in connection with the trunk-line leading to some 25 connector C, and establishing a guarding potential by way of the private normal conductor 79 (Fig. 2) with the connector private bank-contact 80, and to all other private bank-contacts that are connected in 30

multiple therewith. The said connector C is also operated to carry its wipers 66, 67 and 68 into engagement with the desired line. If the desired line is busy the connector, as is well-known, is released by the 35 guarding potential found at the private contact of the called line. If the connector is to connect back with the calling line to signal some party subscriber of the calling line the private normal relay 64 then removes 40

the guarding potential at the private bank-contact 80 for an instant to permit the connector to establish the connection. As soon as the selector A is operated from substation #110, for instance, the switch-shaft 45 50 is then raised, and at the first step the switch-shaft springs 80^a and 81 are brought into contact, thereby placing the side of the line to which the spring 80^a is connected in connection with the main battery B. When 55

the side switch is in first position the said connection is established through the rotary line relay 69; when the side switch is in second position through the vertical line relay 59; and when the side switch is in 60 third position through the rotary line relay 72 of the connector. As soon as the rotary line is thus closed it becomes impossible for any other substation (such as the substations D and F) to interfere with the 65 calling substation #110, because as soon

as a switch-hook of one of the other substations D or F (Fig. 2) is raised an energizing circuit is established through the ground controlling relay M of the interfering station, and the substation release 70 ground of the interfering station is thus cut off. The interfering subscriber, finding he can make no connection, and that the line is busy, will restore his receiver and thereby momentarily energize the releasing relay 75 N. It will be noticed that it becomes possible to energize the said relay N after the cut-off-relay M has been pulled up, since the springs 201 and 203 are now in contact, thus placing the release-relay N in 80 connection with the release-spring 204. When the said spring is pressed onto the springs 208 and 207 an energizing circuit is then established through the line relays 85 of the central office apparatus.

In detail the operations and circuits are as follows: If the subscriber at substation #110 (Fig. 1) wishes to call the subscriber at substation #220, he removes his receiver and thus establishes connection between the 90 ground terminal G¹, ground post 38 of the calling device, release-spring 25, and contact-point 31 of the signaling device. He (the calling subscriber) then presses the button 32 twice and the button 33 of the 95 calling device once; again the button 32 twice and the button 33 once; and for the last time the button 32 ten times and the button 33 once. The above ground circuit is established as soon as the switch cam 12 100 permits the ground springs 17 and 18 to come into contact. By pressing the button 32 twice the vertical line relay 59 of the selector A is energized twice, the current flowing in each case from the substation 105 ground through the springs 44 and 43, ground springs 17 and 18 to the ground post 38, thence to the spring 34, vertical line conductor 83, side switch wiper 84, contact-point 85, conductors 86 and 87, vertical line relay 59, bridge-cut-off-relay springs 88 and 89 to the battery-lead 90, thence through battery B to ground G. Each time that the vertical line relay 59 attracts its armature 110 the line relay spring 91 is pressed onto the ground spring 92 and the vertical magnet 54 in turn is energized. The path of the current through the vertical magnet 54 is as follows: from ground G² through the 115 springs 92 and 91, conductor 93, private 120 springs 94 and 95 to the vertical magnet 54, thence to the battery-lead 90 and through battery B to ground G. Each time that the vertical magnet 54 is energized it 125 attracts its armature 96, causing the vertical pawl 97 to engage one of the circular teeth 98, thereby raising the shaft 50 one step at a time. At the first step the release-link 99 is disengaged from the double-dog 130 100, and the vertical dog 101 catches and

135

holds the shaft in its raised position. Also, as soon as the shaft is raised the first step, the switch-shaft springs 80^a and 81 close contact, extending the subscriber's rotary line conductor 102 to the side switch wiper 103. When the rotary button 33 is pressed the rotary line relay 60 is energized by a flow of current from ground G¹ at the substation to the ground post 38, thence to the 10 spring 35, rotary line conductor 102, switch-shaft springs 80^a and 81, side switch wiper 103, contact-point 104, conductor 105 to the rotary line relay 60, thence to the battery-lead 90 and through battery B to ground G. 15 The rotary line relay upon attracting its armature presses the spring 106 onto the ground spring 92, energizing the private magnet 63.

The energizing circuit for the private magnet is as follows: Beginning from ground G² it extends through the springs 20 92 and 106, conductors 107 and 108 to the private magnet 63, thence to the battery-lead 90 and through battery B to ground G. 25 When the private magnet 63 attracts and releases its armature 109 the escapement-finger 110 clears the teeth 111 and 112 and the side switch K passes to second position. The switch-shaft having been previously 30 raised two steps the switch-shaft wipers 51, 52 and 53 are then opposite the first contact of the second level of their respective banks. It may be assumed that the first nine trunks of the second level are busy, in which case 35 the first nine contacts of the second level of the private bank 56 are connected to ground. When the side switch passes to second position the side switch wiper 113 engages the contact-point 114 and sets up an 40 energizing circuit for the rotary magnet 57. The current flows from ground G³ to the contact-point 114, side switch wiper 113, conductor 115 to the rotary magnet 57, passing through the interrupter-springs 116 and 45 117 to the battery-lead 90 and through battery B to ground G. The shaft 50 will be rotated one step at the first impulse of the rotary magnet, and as a result the private magnet 63 is energized when the private 50 wiper 53 strikes the first grounded contact. The circuit extends from ground G of battery B through whatever selector is occupying the first trunk to the first contact of the second level of the private bank 56, 55 thence through the private wiper 53, conductor 118, back-bridge-relay 62, conductor 119, side switch wiper 120, contact-point 121, conductors 122 and 108 to the private magnet 63, thence to battery-lead 90 and 60 through battery B to ground G. The private magnet 63 will, by keeping its armature 109 attracted, lock the side switch K in second position until the private wiper 65 passes the last busy contact, at which time the energizing circuit for the private mag-

net is broken. The private magnet on de-energizing permits the side switch K to pass to third position, destroying, therefore, the energizing circuit for the rotary magnet 57. Furthermore, as soon as the side switch 70 wipers 84 and 103 engage the contact-points 123 and 124, the subscriber's line conductors 83 and 102 are extended to the line wipers 51 and 52 which are now in connection with the trunk-line leading from the tenth position of the second level of the line bank 75 55. The side switch wiper 120 having at the same time engaged the contact-point 125 a guarding potential is established from ground G⁴ to the private wiper 53 and, 80 therefore, to the tenth contact of the second level of the private bank 56, and to the connector private bank-contacts corresponding to the line that terminates in the selector A, by way of the private normal conductor 79.

Assume that the seized trunk-conductors 126 and 127 and the trunk release conductor 128 leading from the line and private banks 55 and 56 terminate in the connector C, as 90 shown in Figs. 1 and 2. Having established connection with the connector C the calling subscriber by pressing the vertical button 32 twice again energizes the vertical line relay 71 of the connector. The current passes 95 from ground G¹ to the vertical line conductor 83, thence through the side switch wiper 84 to the line wiper 51 and to the vertical trunk-conductor 126. It then flows through the line relay 71 to the battery-lead 90 and 100 through battery B to ground G. The vertical line relay 71 is energized twice and presses the spring 129 onto the ground spring 130. As a result the vertical magnet 73 is energized twice, and the shaft 65 is 105 raised two steps, carrying the shaft wipers 66, 67 and 68 opposite the first contacts of the second level of their respective banks. The energizing circuit for the vertical magnet 73 extends from ground G⁵ through the 110 springs 130 and 129, conductor 131, private springs 132 and 133, conductor 134, side switch wiper 135, contact-point 136 to the vertical magnet 73, thence to the battery-lead 90 and through battery B to ground G. Each time that the vertical magnet 73 becomes energized the armature 137 is attracted, as in the first-selector, and the shaft 65 is operated as described. The rotary button 33 is next pressed once and the rotary line 115 relay 72 of the connector is energized in turn. The energizing current flows from ground G¹ to the rotary line conductor 102, through the switch-shaft springs 80^a and 81 to the side switch wiper 103, line wiper 52 to the rotary trunk-conductor 127, thence through the conductor 138, ringer-relay springs 139 and 140, conductor 141 and through the rotary line relay 72 to the battery-lead 90 and through battery B to 120 130

ground G. The said relay 72 upon attracting its armature presses the spring 142 onto the spring 130, energizing the private magnet 76. Current for energizing said magnet 5 passes from ground G⁵ through the said springs 130 and 142 and conductor 143 to the private magnet 76 and thence to the battery-lead 90 and through battery B to ground G. The private magnet then trips 10 the side switch to second position, shifting the side switch wiper 135 onto the contact-point 144, and thus placing the rotary magnet 74 under the control of the vertical line relay 71. The subscriber then presses the 15 vertical button 32 ten times and again energizes the vertical line relay 71 each time. The rotary magnet 74 is thus energized ten times by a flow of current from ground G⁵ to the side switch wiper 135, thence through 20 the contact-point 144, rotary magnet 74 to the battery-lead 90, and through battery B to ground G. The rotary magnet by attracting its armature 145 ten times rotates the shaft 65 so as to carry the shaft-wipers 66, 25 67 and 68 into engagement with the trunk-line leading from the tenth contacts of the second level of their respective banks. Pressing the rotary button 33 for the last time the subscriber energizes the rotary line relay 72 30 once, and also the private magnet 76 once, thus shifting the side switch L to third position and thus connecting the subscriber's extended line conductors 126 and 127 to the normal conductors 146 and 147, respectively. 35 The conductor 126 is connected with the conductor 146 through the condenser 148 of the connector, conductor 149, ringer-relay springs 150 and 151, side switch wiper 152, contact-point 153, conductor 154, line wiper 40 66 to the conductor 146. It will be seen that the conductor 127 connects with the normal conductor 147 through the condenser 155, conductor 156, ringer-relay springs 157 and 158, side switch wiper 159, contact-point 160, 45 conductor 161 and wiper 67. At the instant that the connector side switch L passes to third position not only is the subscriber's line placed in connection with the called subscriber's line, as shown, but a guarding potential is set up over the seized line to prevent other connectors from interfering. As 50 shown, the guarding potential is established from ground G⁶ to the contact-point 162, side switch wiper 163, conductor 164 and 55 private wiper 68 to the contact-point engaged by the said private wiper and to all other contacts in multiple. Such guarding potential not only protects the seized line but also energizes the bridge-cut-off-relay 60 165 of the called selector A¹ for disconnecting the vertical line relay 166 of the said selector from the battery-lead 90. This is necessary in order to preserve the balanced condition of the line. The energizing circuit through 65 said relay 165 permits a flow of current to pass from ground G⁶ at the connector to the private wiper 68, thence over the private normal conductor 167 of the private normal relay springs 168 and 169, conductor 170, side switch wiper 171, conductor 172 to the 70 bridge-cut-off-relay 165, thence to battery-lead 90 and through battery B to ground G. The said relay 165 upon energizing separates the springs 173 and 174, with the desired result. 75

The calling subscriber now having established connection presses the signaling button 28, thereby grounding the spring 29 on the contact-point 31, and as a result energizing the vertical line relay 71. The current 80 flows from ground G¹ through the springs 44 and 48 and through the ground springs 17 and 18 to the contact-point 31, thence through the spring 29 and through the springs 19 and 20 to the contact-point 36 85 of the calling device, thence through the spring 34 to the vertical line conductor 83, energizing the vertical line relay 71 over the usual path. The vertical line relay again presses the springs 129 and 130 and energizes the ringer-relay 77. The established circuit extends from ground G⁵ through the said springs 130 and 129 to the side switch wiper 135, thence to the contact-point 175, 90 ringer-relay 77 to the battery-lead 90 and 95 through battery B to ground G. The ringer-relay 77 then presses the springs 151 and 158 onto the springs 176 and 177, thus bridging the ringer-generator across the side switch wipers 152 and 159, and, therefore, across the called subscriber's line. The ringing current then passes to the vertical line conductor 178, spring 179, contact-point 180, switch-hook 181, spring 182, ringer 183, condenser 184, contact-point 185, 100 spring 186 to the rotary line conductor 187 and, of course, back to the generator 78. The subscriber at the substation #220 upon 105 hearing the signal will remove his receiver and bridge his secondary circuit across the line in the same manner as described in connection with substation #110. It will be understood, of course, that the ringing current also passes through the ringer at the substation E; but the bell at that station 110 being out of tune with the particular current sent over the line-will not ring—that is, the several subscribers on the party-line are given different numbers, and the normal 115 conductors of the line are multiplied in different connector groups. Each connector group is provided with ringing current of a different character or frequency adapted to operate ringers which are properly tuned or adjusted to correspond to a particular 120 kind of ringing current. Hence, when one subscriber desires to signal another subscriber on the same line, the first-selector is operated to select the particular connector group which is provided with ringing cur- 125 130

rent suitable for operating the ringer at the desired station. The talking circuit over which the calling and called subscribers converse is clearly shown by the heavy lines in Fig. 1. Beginning with the receiver 3 at substation #110, the circuit extends through the secondary winding 8 of the induction-coil 6, contact-point 30, spring 29 and the springs 19 and 20 to the contact-point 36 of the calling device, spring 34, vertical line conductor 83, side switch wiper 84 of the selector A, vertical line wiper 51, conductor 126, condenser 148 of the connector C, conductor 149, ringer-relay springs 150 and 151, side switch wiper 152, vertical line wiper 66, vertical normal conductor 146, vertical line conductor 178, spring 179, contact-point 180, through the secondary winding and the receiver at the substation #220 back to the contact-point 185, spring 186, rotary line conductor 187, rotary normal conductor 147, rotary line wiper 67, side switch wiper 159, ringer-relay springs 158 and 157, conductor 156, condenser 155, conductor 127, wiper 52 of the selector A, side switch wiper 103, switch-shaft springs 81 and 80^a, rotary line conductor 102, spring 35, contact-point 37, condenser 9 back to the receiver 3. If the substation D attempts to use the line after the subscriber #110 has operated his selector A and thereby closed the switch-shaft springs 80^a and 81, the ground controlling relay M will be energized at the instant that the switch-hook closes the springs 188 and 189, before the springs 190 and 191 are separated, since the rotary line conductor 102 is connected to main battery B through some of the relays already described, depending upon the stage of the call.

The relay M will be energized by a flow of current from ground G⁷ through the springs 192 and 193, winding of the relay M, springs 190 and 191, and through springs 188 and 189 to the contact-point 194 of the calling device, thence through the spring 195 to the rotary line conductor 102. If the side switch of the selector A is in first position the circuit will be completed through the rotary line relay 60 and to the battery-lead 90 and to battery B; if in the second position through the vertical line relay 59 to the battery; and if in the third position through the rotary line relay 72 of the connector C to the battery-lead 90 and to the battery. The relay M then energizes or pulls up, and the armature 196 is locked by the latch 197, owing to the pressure of the spring 198. As a result the springs 199 and 200 are forced apart and the spring 201 is shifted from engagement with the spring 202 into engagement with the spring 203, thus placing the release-relay N in series with the ground release-spring 204.

65 When the springs 199 and 200 are forced

apart the substation ground circuit is destroyed and it is impossible for the subscriber to ground the line conductors simultaneously. If he discovers that the line is busy he restores his receiver 205 to the switch-hook, causing the latter to descend, and also permitting the cam 206 to cause the release-springs 207, 208 and 204 to be pressed into contact. An energizing circuit is then established through the release-relay N from ground G⁷ through the said relay N and through the springs 203 and 201, release-spring 208, contact-point 194 and spring 195 to the rotary line conductor 102, and again over a multiple circuit from the spring 208 to the spring 207, contact-point 209, spring 210 to the vertical line conductor 83. The circuit then, of course, extends from the said vertical and rotary line conductors through the line relays of the switches, depending upon the position of the side switch of the selector A, to the battery B.

The paths taken from the rotary line conductor 102 to the main battery have already been pointed out and the path taken from the vertical line conductor 83 to the battery, when the side switch is in first position, is through the vertical line relay 59 of the selector A; and when the side switch is in second position there is no connection to the battery B by way of the vertical line conductor, but only by way of the rotary line conductor; and when the side switch is in third position the battery B is reached through the vertical line relay 71 of the connector C. These circuits, of course, have already been traced. At this instant—that is, at the instant that the locked out subscriber hangs up his receiver—the line conductors 83 and 102 are grounded simultaneously through the release-relay N; but said relay is of such high resistance that the relays of the switches are unaffected and, therefore, such momentary grounding does not interfere with the desired results. As soon as the relay N energizes the armature 211 is attracted and the latch 197 is removed from in front of the armature 196 by the lug 212 and the said armature 196 prevented from returning to its normal position too quickly by the lug 213 to prevent the springs 203 and 201 from separating prematurely.

Not only does the armature 211 control the armature 196, but also the springs 193 and 192, so as to prevent the relay M from energizing at a time when the armature 196 should be free to regain its normal position, namely at the time when the relay N is energized, for otherwise the relays M and N would be energized in multiple. The resistance of such multiple connection would be very low and, in fact, low enough to cause trouble by the raising and lowering of the switch-hook. Referring now to the called

line, it will be noticed that there are no relays across the line between the called subscriber's line and the connector after the bridge-cut-off-relay 165 disconnects the battery B from the vertical line relay 166. As a result the substations, such as the substation E, cannot interfere with the established connection, since it makes no difference how much they operate their calling mechanism or signaling or ringing devices. Grounding either the vertical or rotary line conductors 178 or 187, or both, can energize no apparatus at the central office; therefore, it is not necessary to provide means for cutting off the ground connection of the substations on the called line.

After the subscribers #110 and #220 are through talking the subscriber #110 may release the switching apparatus by restoring his receiver 3 to the switch-hook 2 and thereby pressing the release-springs 25, 26 and 27 into contact. By pressing the release-springs together the vertical and rotary line conductors 83 and 102 are grounded simultaneously from the ground terminal G¹, and as a result the vertical and rotary line relays 71 and 72 of the connector C are energized simultaneously. The path from ground G¹ to the said conductors 83 and 102 is as follows: From ground G¹ through the springs 44 and 43, through the ground springs 17 and 18 and through the springs 42 and 41 to the release-spring 25, thence by way of the release-springs 26 and 27 to the said line conductors.

Energizing the line relays 71 and 72 of the connector simultaneously forces the trunk-release-springs 214 and 215 together and establishes an energizing circuit that comprises the release-magnet 75 of the connector C and back-release-relay 62 of the selector A. The current through this circuit may be traced from ground G¹ at the selector A to the contact-point 125, side switch wiper 120, conductor 119, back-release-relay 62, conductor 118, private wiper 53, trunk release conductor 128, trunk release springs 214 and 215 to the release-magnet 75, thence to the battery-lead 90 and through battery B to ground G. As a result the release-magnet 75 attracts its armature and releases the connector-shaft and side switch; and the back-release-relay 62 of the selector upon bringing the springs 216 and 217 into engagement establishes an energizing circuit through the release-magnet 58 of the first-selector, which release-magnet 58 then attracts its armature 218 in order that the release-link 99 may latch and hold the double-dog 100 in readiness to restore the switch when the release-springs at the substation are opened. It will be evident, of course, that as soon as the connector private wiper 68 leaves the engaging contact the energizing circuit through the bridge-cut-

off-relay 165 of the selector A¹ is broken, and the said relay is restored to normal condition, returning the vertical line relay 166 to normal connection with the battery-lead 90. As soon as the said springs separate the energizing circuit for the line relays 71 and 72 of the connector is destroyed so that the trunk release springs 214 and 215 separate to deenergize the release-magnet 75 of the connector, the back-release-relay 62 of the first-selector, and the release-magnet 58 of the said selector. When the release-magnet 58 deenergizes the release-armature 218 returns to normal position, carrying the double-dog to normal position, and permitting the shaft 50 to be restored at the same time that the side switch K is restored.

It is thus clear how a subscriber of one party line may call a subscriber of another party line. It will now be explained how a subscriber of one party line may call another subscriber of the same party line. For instance, referring to Fig. 2, it may be assumed that the subscriber at substation #110 calls the subscriber at substation #210. In making the call the subscriber at substation #110 removes his receiver 3 from the switch-hook 2 and then presses the button 32 twice and the button 33 once; again the button 32 once and the button 33 once; and for the last time the button 32 ten times and the button 33 once. By operating his calling device in this manner the shaft 50 of the selector A, as already described, is raised two steps and the wipers are rotated along the second level of the line and private banks. Assuming again that the first nine contacts are busy, the wipers will arrive on the tenth contacts of the second level of the line and private banks, from which a trunk-line leads to the connector C, as already described. It will be remembered that as soon as the selector side switch passes to third position the side switch wiper 120 engages the contact-point 125 and a guarding potential is established at the connector private bank-contact 80. The subscriber in continuing to operate his calling device raises the connector-shaft to the first level and then rotates it ten steps, carrying the wipers into engagement with the normal conductors 219 and 220 that lead back onto the calling line.

It has been described how after the selector has trunked to the connector the connector rotary line relay 72 is energized each time that the rotary line conductor 102 is grounded. It will be noticed, furthermore, that the private normal relay 64 of the selector A is energized at the same time. The current for energizing said relay 64 flows from the substation ground G¹ to the rotary line conductor 102, when the rotary button 33 is pressed, thence through the switch-shaft springs 80^a and 81, side switch wiper 103, contact-point 124, to the said relay 64, 130

thence to the battery-lead 90 and through battery B to ground G. Each time that the said relay is energized, of course, connection between the connector private bank-
5 contact 80 and the selector ground terminal G⁴ is interrupted at a point between the private normal relay springs 221 and 222. Therefore, after the calling subscriber has brought his connector wipers into engage-
10 ment with the normal conductors 219 and 220, as described, by pressing the vertical button 32 ten times, corresponding to the third digit of the number 210, and at the instant that he grounds his rotary line
15 conductor 102 by pressing the button 33, he not only energizes the private magnet 76, but he also energizes the private normal relay 64 and cuts off the guarding potential from the contact-point 80. As soon as the
20 impulse is interrupted the private magnet 76 as well as the private normal relay 64 deenergize; but the private springs 223 and 224 separate and the side switch es-
25 capes to third position before the guarding potential is returned to the contact-point 80. Were not the guarding potential thus re-
26 moved the connector would be released at the instant that the private springs 223 and 224 come into contact upon the energization
30 of the private magnet. The energizing cir-
35 circuit for releasing the connector would extend from the contact-point 80 (which is grounded) to the private wiper 68, thence to the conductor 164, side switch wiper 163,
35 contact-point 225, conductor 226, private springs 223 and 224, release-magnet 75 to the battery-lead 90. The release-magnet 75 upon energizing will, of course, release the connector. This is also the case whenever
40 the connector attempts to establish connec-
45 tion with a busy line. Having established connection with his own line, as described, the calling subscriber signals back on his own line and rings the bell of the desired station #210, since the ringer-generator 78, controlled by the connector C, produces a current of a frequency that will affect only the bell of the substation #210 of the calling line, as previously explained. The sub-
50 scriber #210 upon answering removes his bell from across the line and substitutes instead his receiver 227 in series with the secondary winding 228 of the induction-coil 229. Clearly, then, the two subscribers may
55 converse over the line conductors 83 and 102 which connect them. It will be under-
60 stood, of course, that when the subscriber at substation F removes the receiver from the switch-hook the lock-out relay of this sub-
65 station also operates. If while the two sub-
scribers are connected or at any time when the selector A has been operated the sub-
scriber D, for instance, attempts to use the line he will be locked out in a manner that
65 has been previously described—that is, since

the rotary line conductor 102 is connected to main battery the relay M will be energized as in the previous case. If he restores his receiver he will in turn energize the release-relay N, which will restore his apparatus to normal condition. After the calling and called subscribers #110 and #210, respectively, are through talking the former may release the switching apparatus by hanging up his receiver and thereby ground-
70 ing both line conductors simultaneously. As a result, of course, the vertical and rotary line relays 71 and 72 of the connector will again energize simultaneously, establishing an energizing circuit through the release-
75 magnet 75 of the connector and the back-
release-relay 62 of the selector A. The connector-shaft is at once restored, as well as the connector side switch. The back-release-
80 relay 62, as is well known, in turn energizes the release-magnet 58 of the selector, and when the release-springs 25, 26 and 27 of the substation separate the switches are then fully restored in the usual and well-known manner. The substation relays may be
85 mounted upon a separate and independent base, as shown in Figs. 5, 6, 7, 8 and 9. The relays H and I are inclosed in a frame O and secured thereto by screws 230 and 231. The armature 39 of the relay H is pivoted
90 upon an upwardly-projecting section 232 of the frame O, very clearly shown in Fig. 9. The said armature has a downwardly-projecting section 233 which controls the
95 springs 40, 41 and 42 in one group and the
100 springs 43 and 44 in another group. The springs 41 and 43, since they bear continually upon the said section 233, act as restoring springs for the said armature 39. The armature 47 in a similar manner is pivoted upon another upwardly-extending projection 234, clearly shown in Fig. 5, which armature, like the armature 39, is provided with a downwardly-projecting section 235
105 for controlling the springs 48 and 49.
110

The spring 49, being always in engage-
ment with the section 235, acts as a restoring
spring for the armature 47. The member
236 of the armature for controlling the latch
45 is clearly shown in Fig. 5. The said
115 latch, as shown in Fig. 5 and also in Fig. 7, is pivoted between the lugs 237 and 238 and is controlled by the retracting spring 46. The two faces 239 and 240 of the frame O
120 are made rigid by means of the cross-piece 241 which is supported by the screws 242 and 243. The lateral member 244 that projects from the armature 47 of the relay I is designed to control the armature 39 of the
125 relay H, so that when the arm 236 removes the link 45 from the armature 39 the latter may then be able to rise sufficiently to barely clear the edge of the link 45, but not suffi-
130 ciently to separate the springs 40 and 41. The base P to which the frame O may be

secured can be of any suitable material, of course, and is provided with terminals 245 for receiving the ends of the conductors leading to and from the relays H and I and the springs they control.

5 The substation coils H and I may be of any suitable resistance, but it is found that good results are obtained when they are wound to thirteen hundred ohms each. The 10 private normal relay 64 of the first-selector is wound to a resistance of five hundred ohms. The battery can be of 50 volts.

From the foregoing it will be seen that I provide an improved arrangement whereby 15 one party line subscriber cannot interfere with the use of the line by another subscriber who is on the same line and who is already in possession of the line for either talking or switching or signaling purposes.

20 The so-called release-relay of each substation not only controls the circuit of its associated ground controlling relay, but also has a mechanical control over the armature of the said ground controlling relay. With 25 this arrangement the subscriber's station is adapted for electrically operating the ground controlling relay, so that the downward movement of the switch-hook electrically restores the ground controlling relay 30 to normal condition. In this way the two relays can be embodied in one unitary structure, and located at any suitable or desired distance from the subscriber's telephone, thus making it possible to conveniently employ 35 desk telephone sets in connection with a party line system of this particular character. With such provision no extension or party line subscriber can in any way interfere with the use of the line by another subscriber already in possession of the line.

This application shows and describes apparatus similar to that which is shown and which is being claimed in certain other of my co-pending applications. However, the 45 apparatus shown in this application differs from that shown in the above mentioned co-pending application in certain respects, to-wit: each substation on a party line in the present application is provided with a pair 50 of magnets, which magnets work in conjunction to control the lock-out mechanism of each subscriber's individual substation; in that one of the line relays of the individual first selector switches is permanently connected 55 to one pole of the battery; and in that the private normal control relay, that is, the relay which controls the private normal, is permanently connected to one pole of the battery and is excluded from the talking 60 circuit. The claims are restricted to one or more of these features.

What I claim as my invention is:—

1. In an extension or party line telephone system, a telephone line, a plurality of subscribers' telephones connected therewith, au-

tomatic switches, a ground connection at each telephone; means by which said ground connections may be employed for transmitting electrical impulses over the telephone line to operate said automatic switches, a 70 ground controlling relay for each telephone, and a release-relay for each ground controlling relay, said relays being excluded from the talking circuit.

2. In an extension or party line telephone 75 system, the combination of a telephone line, a plurality of subscribers' telephones connected therewith, automatic switches, a ground connection at each telephone, means by which said ground connections may be 80 employed for transmitting electrical impulses over the telephone line to operate said automatic switches, a ground controlling relay for each telephone, and a release-relay for each ground controlling relay, 85 each release-relay provided with means for mechanically restoring its associated ground controlling relay to normal condition.

3. In an extension or party line telephone system, the combination of a telephone line, 90 a plurality of subscribers' telephones connected therewith, automatic switches, a ground connection at each telephone, means by which said ground connections may be 95 employed for transmitting electrical impulses over the telephone line to operate said automatic switches, a ground controlling relay for each telephone, and a release-relay for each ground controlling relay, each release-relay provided with means for both 100 electrically and mechanically controlling its associated ground controlling relay.

4. In an extension or party line telephone system, the combination of a telephone line, a plurality of subscribers' telephones connected therewith, automatic switches, a ground connection at each telephone, means by which said ground connections may be 105 employed for transmitting electrical impulses over the telephone line to operate 110 said automatic switches, a ground controlling relay for each telephone, a release-relay for each ground controlling relay, each ground controlling relay provided with an armature, and means for latching said armature in its attached position, each release-relay provided with means for unlatching 115 said armature.

5. In an extension or party line telephone system, the combination of a telephone line, 120 a plurality of subscribers' telephones connected therewith, automatic switches, a ground connection at each telephone, means by which said ground connections may be 125 employed for transmitting electrical impulses over the telephone line to operate said automatic switches, a ground controlling relay for each telephone, and a release-relay for each ground controlling relay, each ground controlling relay having a grounded 130

energizing circuit including both sides of the telephone line, said energizing circuit controlled by its allotted release-relay.

6. In a telephone exchange system, a telephone line, a subscriber's telephone connected therewith, automatic switches, a ground connection associated with the subscriber's telephone, means by which the subscriber may use the said ground connection for transmitting electrical impulses over the telephone line to operate said automatic switches, a relay controlling said ground connection, said relay provided with an armature, means for latching said armature in its attracted position, and an electro-magnetic device for unlatching said armature.

7. In a telephone exchange system, a telephone line, a subscriber's telephone connected therewith, automatic switches, a ground connection associated with the said telephone, means by which the subscriber may use the said ground connection for transmitting electrical impulses over the telephone line to operate said automatic switches, a relay controlling said ground connection, an energizing circuit for said relay, and another relay for controlling said energizing circuit.

8. In a telephone exchange system, a telephone line, a plurality of subscribers' telephones connected therewith, a ground connection allotted to each telephone, automatic switches, means by which the subscribers may employ said ground connections for transmitting electrical impulses over the said telephone line to operate said automatic switches, a ground controlling relay for each telephone, an electro-magnetic device allotted to each relay, provided with means for controlling the relay, and a subscriber's switch-hook for each telephone, each switch-hook provided with connections for electrically controlling its allotted electro-magnetic device.

45 9. In a telephone exchange system, a telephone line, a plurality of subscribers' telephones connected therewith, a switch-hook for each telephone, a ground connection for each telephone, automatic switches, means by which the subscribers may employ the said ground connections for transmitting electrical impulses over the telephone line to operate said automatic switches, a ground controlling relay for each telephone, each 55 relay provided with an armature, means for latching the armature in its attracted position, and means for electrically unlatching or restoring said relays by the downward movement of their respective switch-hooks.

10. In a telephone exchange system, a telephone line, a subscriber's telephone connected therewith, an automatic switch, a ground connection allotted to the telephone, means by which the subscriber may employ

said ground connection for transmitting electrical impulses over the telephone line to operate said switch, a plurality of grounded line circuits including the said ground connection, and a plurality of relays 70 associated with said telephone and provided with means for controlling said circuits.

11. In a telephone exchange system, an automatic first-selector switch provided with bank-contacts, a wiper adapted to engage 75 said contacts, means for operating said wiper, a battery, a relay permanently connected in series between said wiper and one pole of said battery, and a talking circuit excluding the winding of said relay.

80 12. In a telephone exchange system, the combination of an automatic first-selector switch provided with bank-contacts, a wiper adapted to engage said contacts, means for operating said wiper, a battery, a relay permanently connected in series between said wiper and one pole of said battery, a talking 85 circuit excluding the winding of said relay, and a private normal conductor controlled by said relay.

90 13. In a telephone exchange system, an automatic first-selector switch provided with bank-contacts, vertical and rotary line wipers for engaging said contacts, means for operating said wipers, a battery, a relay permanently connected in series between the rotary line wiper and one pole of said battery, and a private normal circuit controlled by said relay.

95 14. In a telephone exchange system, the 100 combination of an automatic first-selector switch provided with bank-contacts, vertical and rotary line wipers for engaging said contacts, means for operating said wipers, a battery, a relay permanently connected in 105 series between the rotary line wiper and one pole of said battery, a private normal circuit controlled by said relay, and a talking circuit excluding the winding of said relay.

110 15. In a telephone exchange system, an automatic first-selector provided with a pair of normally bridged relays, a battery having one pole grounded and the other pole connected with the bridge at a point between said relays, the battery being permanently connected with the winding of one relay, and means for disconnecting the other relay from the battery.

115 16. In a telephone exchange system, trunk-lines, an automatic trunk-selecting 120 switch mechanism provided with a pair of normally bridged line relays, a battery having one pole grounded and the other pole connected to the bridge at a point between said relays, one relay having its winding 125 permanently connected with the battery, and a bridge-cut-off-relay for severing the connection between the other relay and the battery.

130 17. In a telephone exchange system, a

telephone line, trunk-lines, an automatic trunking switch individual to the said telephone line, said switch provided with a pair of normally bridged line relays, a battery having one pole connected with ground and the other pole connected to the bridge at a point between said relays, one relay having its winding permanently connected with the battery, and a bridge-cut-off-relay for severing the connection between the other relay and the battery.

18. In a telephone exchange system, an automatic switch provided with a pair of normally bridged line relays, a battery having one pole grounded and the other pole normally connected to the bridge at a point between said relays, one relay having its winding permanently connected with the battery, and means for severing connection between the other relay and the battery.

19. In a telephone exchange system, the combination of an automatic first-selector provided with a pair of normally bridged relays, a battery having one pole grounded and the other pole connected with the bridge at a point between said relays, the battery being permanently connected with the winding of one relay, means for disconnecting the other relay from the battery, a talking circuit, and means for disconnecting both relays from the talking circuit.

20. In a telephone exchange system, the combination of trunk-lines, an automatic trunk-selecting switch mechanism provided with a pair of normally bridged line-relays, a battery having one pole grounded and the other pole connected to the bridge at a point between said relays, one relay having its winding permanently connected with the battery, a bridge-cut-off-relay for severing the connection between the other relay and the battery, a talking circuit, and means for disconnecting both relays from the talking circuit.

21. In a telephone exchange system, the combination of a telephone line, trunk-lines, an automatic trunking switch individual to the said telephone line, said switch provided with a pair of normally bridged line relays, a battery having one pole connected with ground and the other pole connected to the bridge at a point between said relays, one relay having its winding permanently connected with the battery, a bridge-cut-off-relay for severing the connection between the other relay and the battery, a talking circuit, and means for disconnecting both relays from the talking circuit.

22. In a telephone exchange system, the combination of an automatic switch provided with a pair of normally bridged line relays, a battery having one pole grounded and the other pole normally connected to the bridge at a point between said relays, one relay having its winding permanently con-

nected with the battery, means for severing connection between the other relay and the battery, a talking circuit, and means for disconnecting both relays from the talking circuit.

23. In an extension or party line telephone system, the combination of a telephone line, a plurality of subscribers' telephones connected therewith, automatic switches, a ground connection at each telephone, means by which said ground connections may be employed for transmitting electrical impulses over the telephone line to operate said automatic switches, a ground controlling relay for each telephone, a release-relay for each ground controlling relay, said automatic switches including connectors, means for permitting a connector to establish connection with the calling telephone line, and means by which the calling subscriber may then produce an audible call-signal at the telephone of the called subscriber on the same line.

24. In an extension or party line telephone system, the combination of a telephone line, a plurality of subscribers' telephones connected therewith, automatic switches, a ground connection at each telephone, means by which said ground connections may be employed for transmitting electrical impulses over the telephone line to operate said automatic switches, a ground controlling relay for each telephone, a release-relay for each ground controlling relay, each release-relay provided with means for mechanically restoring its associated ground controlling relay to normal condition, said automatic switches including connectors, means for permitting a connector to establish connection with the calling telephone line, and means by which the calling subscriber may then produce an audible call-signal at the telephone of the called subscriber on the same line.

25. In an extension or party line telephone system, the combination of a telephone line, a plurality of subscribers' telephones connected therewith, automatic switches, a ground connection at each telephone, means by which said ground connections may be employed for transmitting electrical impulses over the telephone line to operate said automatic switches, a ground controlling relay for each telephone, a release-relay for each ground controlling relay, each release-relay provided with means for both electrically and mechanically controlling its associated ground controlling relay, said automatic switches including connectors, means for permitting a connector to establish connection with the calling telephone line, and means by which the calling subscriber may then produce an audible call-signal at the telephone of the called subscriber on the same line.

26. In an extension or party line telephone system, the combination of a telephone line, a plurality of subscribers' telephones connected therewith, automatic switches, a ground connection at each telephone, means by which said ground connections may be employed for transmitting electrical impulses over the telephone line to operate said automatic switches, a ground controlling relay for each telephone, a release-relay for each ground controlling relay, each ground controlling relay provided with an armature, means for latching said armature in its attracted position, each release-relay provided with means for unlatching said armature, said automatic switches including connectors, means for permitting a connector to establish connection with the calling telephone line, and means by which the calling subscriber may then produce an audible call-signal at the telephone of the called subscriber on the same line.

27. In an extension or party line telephone system, the combination of a telephone line, a plurality of subscribers' telephones connected therewith, automatic switches, a ground connection at each telephone, means by which said ground connections may be employed for transmitting electrical impulses over the telephone line to operate said automatic switches, a ground controlling relay for each telephone, a release-relay for each ground controlling relay, each ground controlling relay having a grounded energizing circuit including both sides of the telephone line, said energizing circuit controlled by its allotted release-relay, said automatic switches including connectors, means for permitting a connector to establish connection with the calling telephone line, and means by which the calling subscriber may then produce an audible call-signal at the telephone of the called subscriber on the same line.

28. In a telephone exchange system, the combination of a telephone line, a plurality of subscribers' telephones connected therewith, a ground connection allotted to each telephone, automatic switches, means by which the subscribers may employ said ground connections for transmitting electrical impulses over the said telephone line to operate said automatic switches, a ground controlling relay for each telephone, an electro-magnetic device allotted to each relay, provided with means for controlling the relay, a subscriber's switch-hook for each telephone, each switch-hook provided with connections for electrically controlling its allotted electro-magnetic device, said automatic switches including connectors, means for permitting a connector to establish connection with the calling telephone line, and means by which the calling subscriber may then produce an audible call-

signal at the telephone of the called subscriber on the same line.

29. In a telephone exchange system, the combination of a telephone line, a plurality of subscribers' telephones connected therewith, a switch-hook for each telephone, a ground connection for each telephone, automatic switches, means by which the subscribers may employ the said ground connections for transmitting electrical impulses over the telephone line to operate said automatic switches, a ground controlling relay for each telephone, each relay provided with an armature, means for latching the armature in its attracted position, means for electrically unlatching or restoring said relays by the downward movement of their respective switch-hooks, said automatic switches including connectors, means for permitting a connector to establish connection with the calling telephone line, and means by which the calling subscriber may then produce an audible call-signal at the telephone of the called subscriber on the same line.

30. An automatic party-line telephone system comprising cut-off and release relays at each of the substations on a party line, the substations being in multiple, substation apparatus governed thereby, and means including automatic switches for extending connection from said party-line.

31. In a telephone system, a party-line, a plurality of substations on said line, the substations being in multiple, a relay at each substation, said relays controlling the use of the line for make-and-break impulse-transmitting purposes, and electromagnets operatively connected with the armatures of the said relays, for restoring said relays to normal position.

32. In a telephone system, a party-line, suitable means for extending connection to or from said line, and a plurality of relays for each substation on said party-line, controlling circuits thereof, said relays adapted to prevent interference between the different subscribers on the same line in extending a connection therefrom, said relays having no control over the talking circuit.

33. In a telephone system, a line, a plurality of telephones connected therewith, means for extending a connection therefrom, and means for preventing interference between the different subscribers in extending a connection from said line, said means comprising a pair of substation-controlled relays for each telephone, one relay of each pair controlling the energizing circuit through the other, said relays having no control over the talking circuit.

34. In an extension or party-line telephone system, a telephone line, a plurality of subscribers' telephones connected therewith, automatic switches having vertical

motion to select groups and rotary motion to connect with a line in any selected group, a ground connection at each telephone, means by which said ground connections 5 may be employed for transmitting electrical impulses over the telephone line to operate said automatic switches, a ground-controlling relay for each telephone, and a release relay for each ground-controlling relay, 10 said relays being excluded from the talking circuit.

35. In a telephone exchange system, a telephone line, a subscriber's telephone connected therewith, automatic switches having 15 vertical motion to select groups and rotary motion to connect with a line in any selected group, a ground connection at the subscriber's telephone, means by which the subscriber may use the said ground connection 20 for transmitting electrical impulses over the telephone line to operate said automatic switches, a relay controlling said ground connection, said relay provided with an armature, means for latching said armature 25 in its attracted position, and an electromagnetic device for unlatching said armature.

36. In a telephone exchange system, a telephone line, a subscriber's telephone connected therewith, automatic switches having 30 vertical motion to select groups and rotary motion to connect with a line in any selected group, a ground connection associated with the said telephone, means by which the subscriber may use the said ground connection 35 for transmitting electrical impulses over the telephone line to operate said automatic switches, a relay controlling said ground connection, an energizing circuit for said relay, and another relay for controlling said 40 energizing circuit.

37. In a telephone exchange system, a telephone line, a plurality of subscribers' telephones connected therewith, a ground connection allotted to each telephone, automatic 45 switches having vertical motion to select groups and rotary motion to connect with a line in any selected group, means by which the subscribers may employ said ground connections for transmitting electrical impulses over the said telephone line to operate said automatic switches, a ground-controlling relay for each telephone, an electromagnetic device allotted to each relay, provided with means for controlling the 50 relay, and a subscriber's switch-hook for each telephone, each switch-hook provided with connections for electrically controlling its allotted electromagnetic device.

38. In a telephone exchange system, a 55 telephone line, a plurality of subscribers' telephones connected therewith, a switch-hook for each telephone, a ground connec-

tion for each telephone, automatic switches having vertical motion to select groups and rotary motion to connect with a line in any 60 selected group, means by which the subscribers may employ the said ground connections for transmitting electrical impulses over the telephone line to operate said automatic switches, a ground-controlling relay 65 for each telephone, each relay provided with an armature, means for latching the armature in its attracted position, and means for electrically unlatching or restoring said relays by the downward movement of their 70 respective switch-hooks.

39. In a telephone exchange system, a telephone line, a subscriber's telephone connected therewith, an automatic switch having vertical motion to select groups and 75 rotary motion to connect with a line in any selected group, a ground connection allotted to the telephone, means by which the subscriber may employ said ground connection for transmitting electrical impulses over the 80 telephone line to operate said switch, a plurality of grounded line circuits including the said ground connection, and a plurality of relays associated with said telephone and provided with means for controlling said 85 circuits.

40. In a telephone system, a party-line, a plurality of relays for each of the substations thereof, the substations being in multiple, automatic switches controllable 90 over the said line, and means whereby said relays preclude interference between the subscribers in the use of said switches.

41. In an automatic telephone system, a party-line, a plurality of relays for each of the substations thereof, the substations being in multiple, hook-switches controlling the circuits of said relays, an automatic switch, and means at said substations for controlling said switch for extending connection 100 from said party-line.

42. In a telephone system, a telephone line having one side thereof normally open at the exchange or central station, a substation on said line provided with a pair of relays, means controlled from said substation on said line for closing said normally open connection in the talking circuit, an energizing circuit for one of said relays which includes the said normally open connection, 105 a vertical and rotary switch shaft, and operating circuits controlled by said relay for controlling said shaft.

Signed by me at Chicago, Cook county, Illinois, this 11th day of June, 1906.

TALBOT G. MARTIN.

Witnesses:

EDWARD D. FALES,
B. D. WILLIS.

It is hereby certified that in Letters Patent No. 1,123,339, granted January 5, 1915, upon the application of Talbot G. Martin, of Chicago, Illinois, for an improvement in "Telephone-Exchange Systems" an error appears in the printed specification requiring correction as follows: Page 9, line 116, for the word "attached" read *attracted*; and that the said Letters Patent should be read with this correction therein that the same may conform to the record of the case in the Patent Office.

Signed and sealed this 26th day of January, A. D., 1915.

[SEAL.]

R. F. WHITEHEAD,

Acting Commissioner of Patents.
